 mensstadt, Berlin, Germany, a corporation of
 Germany

Application August 15, 1936, Serial No. 96,198
 In Germany August 15, 1935

9 Claims. (Cl. 175—41)

This invention relates to a novel electrical condenser in rod or tubular form.

The rapid development of radio technology has increased the demand for properly balanced 5 condensers, especially those of very small capacity values.

It is known from the prior art that the capacity value of roll condensers, after their manufacture, may be varied by removal of portions of 10 the coats, the parts to be so removed being pulled out of the roll or wrap and then shortened. However, a method of this kind is liable to lead to damaging of the condenser to an extent where it is rendered unserviceable, especially in the case 15 of electrical condensers where the metallic coats or foils are wound on a rod or tubular form made from laminated mica, styroflex, or similar insulation materials which may be used for the dielectric, and more particularly in condensers of 20 extremely reduced capacity in which the coat comprises only one turn and even less.

Now, the present invention is concerned with an electrical condenser of bar, rod or tube shape, especially of the kind hereinbefore mentioned.

According to this invention, at least one condenser coat is subdivided into strips which at one end are united comb-fashion, for instance, so that by the severance of such strips the capacity value is readily alterable.

One essential merit of the arrangement as here disclosed resides in the fact that the capacity balance or adjustment need to be effected only after the condenser body has been completed so that undesirable changes in capacity 35 and damage to the dielectric will not happen.

One exemplified embodiment of the invention is illustrated in the drawing.

Fig. 1 shows schematically the development of a condenser;

Fig. 1A is a condenser development similar to Fig. 1, except that both conductive strips are slotted and placed in staggered relationship with each other;

Fig. 2 shows a bar-shaped condenser in elevation comprising a portion of the coats protruding from the condenser body.

The adjusting metallic coat 1 has one or more long slots 5 which project beyond the edge of the insulation material 3 serving as the dielectric so that the coat 1 comprises several strips 6, which strips may have different lengths projecting within the condenser body as shown to the left of Fig. 1. After the roll has been completed, in a way as shown by short dash lines at 55 4, any desired number of strips may be severed

from the coat 1 until the desired capacity results. Also shown by Fig. 1A, the cooperative coat 2 could be shaped in a similar way so that, if the two coats are suitably disposed geometrically, for example, by that opposite strips or slots are staggered in reference to one another, a capacity balance in fine steps or gradations is feasible. 7 and 8 designate the terminal electrodes of coats 1 and 2.

Referring to Fig. 2, one coat, 10, has incised 10 strips 11, whereas the other coat 12 is continuous. 13 designates the resultant condenser body.

It may be mentioned that the strips 6 as shown in Fig. 1 may also be made of dissimilar length and width.

What is claimed is:

1. An electrical condenser comprising a first conducting strip, a second conducting strip, at least one end portion of said conducting strips being slotted comb-shape, an insulating member 20 interposed between said first and second conducting strips in a manner such that the closed side of the slotted portion extends beyond said insulating strip so that the condenser capacity 25 may be adjusted by a severance of a part of the slotted portion.

2. An electrical condenser comprising a bar on which is wound a first conducting strip, a second conducting strip, at least one end portion of said conducting strips being slotted comb-shape, an insulating member interposed between 30 said first and second conducting strips in a manner such that the closed side of the slotted portion extends beyond said insulating strip so that the condenser capacity 35 may be adjusted by severance of a part of the slotted portion.

3. An electrical condenser having electrodes wound in tube form comprising a first conducting strip, a second conducting strip, at least one end portion of said conducting strips being slotted 40 comb-shape, an insulating tube-like member interposed between said first and second conducting strips in a manner such that the closed side of the slotted portion extends beyond said insulating strip so that the condenser capacity 45 may be adjusted by severance of a part of the slotted portion.

4. An electrical condenser comprising a first conducting strip, a second conducting strip having one end portion slotted comb-shape, the slotted portion being arranged so as to provide strips of conducting material of different lengths, an insulating member interposed between said first and second conducting strips in a manner such 50 that the closed side of the slotted portion ex- 55

tends beyond said insulating strip so that the condenser capacity may be adjusted by severence of a part of the slotted portion.

5. An electrical condenser comprising a first conducting strip, a second conducting strip having one end portion slotted comb-shape, the slotted portion being arranged so as to provide strips of conducting material of different widths, an insulating member interposed between said first and second conducting strips in a manner such that the closed side of the slotted portion extends beyond said insulating strip so that the condenser capacity may be adjusted by severence of a part of the slotted portion.

15. An electrical condenser comprising two conducting strips, one end portion of each strip being slotted comb-shape, an insulating member interposed between said conducting strips, the slots in said conducting strips being in staggered relationship with respect to each other and having the slotted portion extending beyond said insulating strip so that the condenser capacity may be adjusted by severence of a part of said slotted portion.

25. An electrical condenser comprising a bar on which is wound two conducting strips having a plurality of conductor turns around said bar, at least one end portion of said conducting strips being slotted comb-shaped, an insulating member

interposed between said first and second conducting strips in a manner such that the closed side of the slotted portion extends beyond said insulating member so that the condenser capacity may be adjusted by severence of a part of the slotted portion.

5. An electrical condenser comprising a bar on which is wound two conducting strips having a single conductor turn around said bar, at least one end portion of said conducting strips being slotted comb-shaped, an insulating member interposed between said first and second conducting strips in a manner such that the closed side of the slotted portion extends beyond said insulating member so that the condenser capacity may be adjusted by severence of a part of the slotted portion.

10. An electrical condenser comprising a bar on which is wound two conducting strips having less than a single conductor turn around said bar, at least one end portion of said conducting strips being slotted comb-shaped, an insulating member interposed between said first and second conducting strips in a manner such that the closed side of the slotted portion extends beyond said insulating member so that the condenser capacity may be adjusted by severence of a part of the slotted portion.

LUDWIG LINDER.
